(57) **CLAIM**

The ornamental design for a cartridge, as shown and described.

DESCRIPTION

The nature of this product is a cartridge comprising a cardboard cartridge box containing (3) replenisher containers in a row for replenishing processing solution to an automatic processor. The cartridge is flipped upside down and inserted into an automatic processor, allowing one-step exchange of the cartridge. The cartridge supplies the solution, is used, and removed as is.

FIG. 1 is a perspective view of the cartridge;

FIG. 2 is a front view thereof;

FIG. 3 is a right side view thereof;

FIG. 4 is a left side view thereof;

FIG. 5 is a top view thereof; and,

FIG. 6 is a bottom view thereof.

The rear view is not part of the claimed design.
